UNITED STATES PATENT OFFICE.

FRANK GURLEY, OF HIGH POINT, NORTH CAROLINA.

DESIGN FOR A PEN-WIPER.

SPECIFICATION forming part of Design No. 33,098, dated August 21, 1900.

Application filed July 18, 1900. Serial No. 24,112. Term of patent 14 years.

To all whom it may concern:

Be it known that I, FRANK GURLEY, a citizen of the United States, residing at High Point, in the county of Guilford and State of North Carolina, have invented and produced a certain new and original Design for a Pen-Wiper; and I do declare the following to be a full, clear, and exact description of the invention, such as will enable others skilled in the art to which it appertains to make and use the same.

The invention relates to a new and original design for a pen-wiper; and it consists of a design of the shape and configuration shown in the accompanying drawings, in which—

Figure 1 is a perspective view, and Fig. 2 is a longitudinal sectional view.

The leading feature of the design comprises a roll 1, from the edges of which project divergent arms 2, the extreme ends of which are provided with laterally-extending heads 3, having opposed corrugations 4, the inner faces of which have a lining 5.

What I claim is—

The design for a pen-wiper, as herein shown and described.

In testimony whereof I have hereunto set my hand in presence of two subscribing witnesses.

FRANK GURLEY.
